US00D976926S

(12) **United States Design Patent** (10) **Patent No.:** **US D976,926 S**
Whyte (45) **Date of Patent:** **** Jan. 31, 2023**

(54) **DISPLAY SCREEN OR PORTION THEREOF
WITH A GRAPHICAL USER INTERFACE**

(71) Applicant: **Snap Inc.**, Santa Monica, CA (US)

(72) Inventor: **David Whyte**, Toronto (CA)

(73) Assignee: **Snap Inc.**, Santa Monica, CA (US)

(**) Term: **15 Years**

(21) Appl. No.: **29/788,624**

(22) Filed: **Jul. 6, 2021**

(51) LOC (14) Cl. **14-04**

(52) U.S. Cl.

USPC **D14/485**

(58) **Field of Classification Search**

(57) **CLAIM**

The ornamental design for a display screen or portion thereof with a graphical user interface, as shown and described.

DESCRIPTION

The FIGURE is a front view of a display screen or portion thereof with a graphical user interface, showing my new design.

The broken lines illustrate the display screen, and the broken lines form no part of the claimed design.

1 Claim, 1 Drawing Sheet
